UNITED STATES PATENT OFFICE.

FRANCIS K. BAXTER, JR., OF SAN FRANCISCO, CALIFORNIA.

CABINET.

Application filed November 5, 1918, Serial No. 261,190. Renewed January 5, 1923.

To all whom it may concern:

Be it known that I, FRANCIS K. BAXTER, Jr., of San Francisco, California, have invented certain new and useful Improvements in Cabinets, whereof the following is a specification.

This invention relates to cases for hanging maps, drawings and other articles, to protect them and make them easily accessible.

The invention may be best understood from the subjoined description of the accompanying two sheets of drawings, in which I have illustrated the invention as applied to the holding of maps and in which:—

Figure 1 is a partial side elevation of the case.

Figure 2 is a sectional face elevation of the case, that is, a map therein would be seen in face.

Figure 3 is a top view of so much of the case as is shown in Figure 1.

Figure 4 is a face view of a map, ready to hang in the case.

Figure 5 is an edge view of the same.

Figure 6 is a mutilated end view of a map carriage, in position to show the face of a contained map.

Figure 7 is a side view of a map carriage, in position to show the edge of a contained map.

Figure 8 is a top view of what is shown in Figure 6.

Figure 9 is an enlarged view of the left hand half of Figure 7, partly in section.

Figure 10 is the same as Figure 7, but with the members spread, or partly separated, also showing portions of maps thereon.

Figure 11 is the same but with the members entirely separated.

Fig. 12 is a cross section thru the hanger bar.

In the drawings: The case A may preferably be in the form of a rectangular box with an open side, which may be protected by a curtain, not shown, hung upon a rod 1, see Figure 2, whereby access is given to the maps. Within the case, at each side is a tramway 2 upon which travel the map carriages 3, mounted on the wheels 4. The tramways 2 include toothed racks 5, see Figure 8, engaged by pinions 6, which serve to keep the members of the carriages in lateral alignment with each other.

Each map carriage comprises four traveling plates, *a*, *b*, *c*, *d*, each of which is hung upon the wheels 4, and pinions 6. These plates are joined together in pairs by the double connector bars 7, and the hanger bars, also double, 8. Cross bars 9 and 10, extending across the case, from side to side, join the analogous plates, *a* and *c*, and *b* and *d*, together, so that they move as a unit, constituting one half of a complete carriage. The double connectors 7 are composed of a sleeve 11 and a rod 12, telescoping thereto, thereby making an extensible bar. A tube 13, secured to the sleeve 11, contains a bolt 14, shot by a spring 15 into notches or holes in the bar 12, to lock the parts together. The sleeves 11 and bars 12 may be attached directly to their respective plates, *c* and *a*, by the brackets 16 and nuts 17, or otherwise. The hangers 8 are constructed similarly to the connectors 7, and are composed of a sleeve 18 and telescoping bar 19, both of which may be slightly shorter than the analogous parts 11 and 12, so that when the latter are extended to their limit, as seen in Figure 10, the former will be nearly or quite separated. A further extension movement of the parts will entirely separate them, as seen in Figure 11. The sleeves 18 and the telescoping bars 19 are respectively attached to and supported by, the lateral cross bars 10, so that the hangers 8 are sufficiently to one side of the connectors 7 to be clear of the locks 13.

The maps are adapted to be hung upon the sleeves and bars 18, 19. For this purpose each map is provided with holes 20 near its edge, and in position to receive those members. These holes may be reinforced by metal clips 21, which may constitute a binding for the edge of the map, as clearly seen in Figures 4 and 5.

The tendency of the maps to tear loose or wear at the holes 20 is overcome by making the tops of these holes with a flat side as shown in Fig. 4.

When the apparatus is in use the maps *e*, *f*, *g*, *h*, *i*, *k*, *l* are strung upon the sleeve 18, as clearly seen in Figures 10 and 11, the sleeve and its bar being first sufficiently separated to permit of the operation. The parts are then approached, to the position shown in Figure 7. Should it be desired to inspect any particular map, as "g," the maps up to and including the one desired to wit; *e*, *f* and *g*, are slid along the sleeve 18 onto the

bar 19 and the plates *a* and *b* separated, as seen in Figure 11. The desired map may then be slipped over the end of bar 19 off the bar and removed to a table.

- 5 In order that the maps may slide readily from sleeve 18 to bar 19, and vice versa, the sleeve is open or slotted at the top as at 22 in Figure 8, and the edges chamfered so that the top of bar 19 and the tops of the chamfered edges of the sleeve are virtually on the same level, as is clearly shown in Figures 8, 9, 10 and 11. The end of the sleeve 18 is also chamfered, for the same purpose, as seen in Figures 10 and 11.
- 10 15 A convenient way of constructing the bars 9 is to make them in the form of spacing sleeves, with tie rods 23 extending through them, as indicated in Figures 6 and 8, which tie rods may extend into the wheels 4 and pinions 6 and constitute stub-axes therefor.

Having thus described my invention, and an embodiment of it, in the full, clear and exact terms required by law, and knowing 25 that it comprises novel, useful and valuable improvements in the art to which it pertains, I here state that I do not wish to be limited to the precise construction and arrangement of the several parts, as herein set 30 forth, as the same may be variously modified by a skilled mechanic without departing from the spirit of the invention.

What I claim and desire to secure by Letters Patent of the United States, is the 35 following, to wit:—

1. In a cabinet, the combination of a structure; a plurality of parallel bars; a series of sleeves each adapted to slide over one of said bars; a carriage to which said 40 bars are secured; a carriage to which said sleeves are secured; and means for supporting said carriages in the said structure in such a manner that they can be separated to pull said bars out of said sleeves.

- 45 2. In a cabinet, the combination of a structure; a plurality of parallel bars; a series of

sleeves each adapted to slide over one of said bars; a carriage to which said bars are secured; a carriage to which said sleeves are secured; means for slidably supporting said carriages in said structure; and releasable means for locking said carriages together. 50

3. In a cabinet, the combination of a structure; a plurality of parallel bars; a series of sleeves each adapted to slide over one of said bars, said sleeves being cut away on a tangent to the top of said rod; a carriage to which said bars are secured; a carriage to which said sleeves are secured; and means for supporting said carriages in said structure in such a manner that they can be separated to pull said bars out of said sleeves. 55

4. In a cabinet, the combination of a structure; a plurality of parallel bars; a series of sleeves each adapted to slide over one of said bars; said sleeves being cut away on a tangent to the top of said rod; a carriage to which said bars are secured; a carriage to which said sleeves are secured; means for slidably supporting said carriages in said structure; and releasable means for locking said carriages together. 60

5. In a cabinet a supporting structure; two carriages adapted to slide in said structure along the same path; two parallel members carried by one of said carriages and projecting towards the other carriage; and two other parallel members secured to the other carriage and projecting towards the first named carriage, each of said members on one carriage being so formed and situated that it will pass readily thru a perforation in a map, when said perforation is occupied by a corresponding member on the other carriage. 65

In testimony, that I claim the foregoing I have hereto set my hand in the presence of two witnesses, this 26th day of Oct., 1918.

FRANCIS K. BAXTER, JR.
